UNITED STATES PATENT OFFICE

142,293

DESIGN FOR AN AERONAUTICAL BOMB

Richard H. Arbib, Jamaica, N. Y., assignor to Republic Aviation Corporation, Farmingdale, N. Y., a corporation of Delaware

Application January 6, 1945, Serial No. 117,316

Term of patent 14 years

(Cl. D71—1)

To all whom it may concern:

Be it known that Richard H. Arbib, a citizen of the United States and a resident of Jamaica, in the county of Queens and the State of New York, has invented a certain new, original, and ornamental Design for Aeronautical Bombs, described and claimed in the following specification and shown in the accompanying drawing wherein:

Fig. 1 is a side elevation of an aeronautical bomb embodying the present design:

Fig. 2 is a plan view thereof:

Fig. 3 is a perspective view thereof; and

Fig. 4 is a front elevation.

What is claimed is:

The ornamental design for an aeronautical bomb, substantially as shown.

RICHARD H. ARBIB.
